UNITED STATES PATENT OFFICE.

JESSE C. LEAR, OF VANDERGRIFT, PENNSYLVANIA.

ROLL HEATER.

Application filed March 9, 1925. Serial No. 14,297.

This invention contemplates the provision of a sheet mill roll heater, by means of which the rolls of the mill can be quickly heated to a temperature prior to the use of the mill, so that a high character or degree of work can be accomplished from the beginning as contra-distinguished from the present method, wherein the rolls are not properly heated until after a considerable length of time incident to the use of the rolls, so that the work done over a period of a day is not of uniform character.

One of the chief characteristics of the present invention resides in the provision of a heater designed to completely enclose or cover the rolls of the mill, and including spaced groups of a series of burners arranged to direct the heat against the surface of the rolls, in a manner whereby the entire surface of each roll is expeditiously heated to a proper temperature to accomplish the best results.

Other objects and advantages of the invention will appear when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is an end elevation showing one embodiment of the invention and the manner of using the same.

Figure 2 is a view taken at a right angle to Figure 1.

Figure 3 is a sectional view taken on line 3-3 of Figure 1.

Figure 4 is an enlarged detail view of the arrangement of one group of burners with relation to the baffle plate against which the heat is directed, the baffle being used to protect the rolls.

Figure 5 is a sectional view showing the arrangement of the air and fuel pipes.

Figure 6 is a view similar to Figure 1 of a modified construction.

Figure 7 is a view taken at a right angle to Figure 6.

Figure 8 is a fragmentary sectional view of the rolls showing the spacing element interposed therebetween.

Figure 9 is a perspective view of the bar

and blocks which are used beneath the rolls to prevent the latter from falling into the pit usually located beneath the rolls of the mill.

Figure 10 is a perspective view of one of the blocks used in connection with the bar, shown in Figure 9.

Figure 11 is a perspective view of the tightening key for the blocks, when used in the manner illustrated in Figure 9.

Figure 12 is a detail view partly in section of the supporting jack for the heater.

Figure 13 is a perspective view of the bar which provides the connection between the roll ends of the respective sections of the heater shown in Figure 6.

Figure 14 is a detail view showing the relative position of the baffle plate with relation to the roll and one of the burners.

Referring to the drawings in detail, and more particularly to Figures 1 to 5 inclusive, I have shown the rolls of the mill at 10 and 11 respectively, and beneath these rolls is arranged the usual bar 12 which prevents the rolls from falling into a pit usually disposed beneath the rolls, in event that one of the rolls should break or become separated from the mill structure as will be readily understood. This bar 12 is usually straight, but when the form of the invention illustrated in Figure 1 is employed, the heater structure extends so far beneath the lowermost roll 11 that it is necessary to provide the bar 12 with an offset or depressed portion 13, as shown in Figure 1. The construction of this bar is clearly illustrated in Figure 9, wherein it will be noted that the offset or depressed portion 13 is formed with a longitudinal slot 14 to accommodate the stems 15 of substantially T-shaped blocks 16 which are used to bring the level of the bar along the intermediate portion thereof, substantially flush with the upper surface of said bar, when the heater is not being used.

In other words, when the heater is associated with the rolls, which is done for an appreciable length of time before the mill is put into operation, it is necessary to have the upper surface of the bar 12 arranged in close proximity to the lowermost roll 11, and it is in order to fill the space formed by the offset or depressed portion 13 of this bar, that I use a block 16 as shown in Figure 10. The blocks are arranged in end to end re-

lation, the slot 14 receiving the stems 15 of said block, and the blocks are held fixed relatively by means of a key 17 shown in Fig. 11. This key is also of substantially T-shaped formation and the stem 18 thereof is adapted to be fitted in the slot 14 as shown in Figure 9. The key is formed with an upstanding lug 19 having an opening 20, while each of the blocks having similar openings 21, the openings being provided to accommodate suitable wire instruments employed to facilitate the removal of the blocks and key from the bar 12 as the occasion requires.

15 The heater forming the gist of the present invention, includes a casing like cover which is designed to completely cover or enclose the rolls of the mill, and it is to be here understood that this casing can be constructed from any suitable material, vary in size and configuration without departing from the spirit of the invention. This casing is preferably made into sections 22 and 23 respectively, which sections may be held 20 associated about the rolls in any suitable manner. The section 22 however is preferably formed with an apertured extension 24 pivoted as at 25 at the lower end of the section, and which extension is adapted 25 to receive the hook 26 carried by the adjacent end of the section 23. The upper ends of these sections are provided with spaced parallel lugs 27, one of which supports an adjusting screw 28 which bears against the 30 other of said lugs so that the sections can be drawn tightly about the rolls for use. The casing is preferably lined with fire clay 29 as shown in Figure 3, while also arranged within the casing are pieces of asbestos 30 which are arranged in right angular relation to the fire clay lining 29 and adapted to engage the rolls as shown in Fig. 3. Arranged exteriorly of the casing are angle iron bars 31, which of course are used to 35 afford the structure the desired strength and rigidity. Arranged on each section of the casing are hooks 32 by means of which the heater in its entirety can be lifted off the rolls after the sections have been separated 40 at the lower ends thereof.

Carried by each section of the casing is 45 a spaced series of burners, the burners of each series being arranged to extend longitudinally of the adjacent roll, this arrangement being clearly shown in Figure 2. Any number of burners may be included in any one series, the burners of one series being indicated generally at 33 in Figure 4, being supported by a pipe 34 which communicates 50 with a pipe 35, these pipes for the respective series of burners being suitably coupled together, and arranged in communication with the air and fuel supply pipes 36 and 37 respectively. It will now be noted that each 55 of the latter mentioned pipes are provided

with valves 38, while each independent burner is provided with a similar valve 39, so that any one of the combination of burners in any or all of the various series of said burners, can be employed when desired. 70 Each of these burners includes a perforated sleeve clearly shown in Figure 4, and these sleeves are adapted to be received by openings provided in the adjacent section of the casing above described, thereby supporting the burners in the manner shown in Figure 1, each section of the casing being provided with additional air inlet openings 40 suitably spaced apart as shown in Figure 2. 75 Arranged within each section of the casing is a baffle plate or bar 41 terminally supported by suitable brackets 42, there being one of these bars for each series of burners, and arranged directly in front of said burners as clearly shown in Figures 4 and 14, the bars being so arranged to protect the rolls as will be readily understood. In order that the heat from these burners will pass about each roll, so that the entire surface of the latter will be heated to a proper 80 temperature, I employ a spacing element indicated at 43, this element being in the nature of an asbestos strip adapted to be interposed between the rolls, to allow the heat to pass therebetween and circulate about both 85 rolls as will be readily appreciated.

90 The invention thus far described is used as follows:

The heater as above stated is intended to 100 be used for an appreciable length of time before the mill is put into operation, so that the rolls will be properly heated to accomplish the best results from the very beginning. Consequently, while the rolls 10 and 11 are idle, the heater is arranged about the 105 rolls, the sections thereof being properly connected together as shown in Figures 1 and 2. Then any combination of burners, or all of said burners can be lighted to heat 110 the rolls to the proper temperature, after which the heater can be conveniently removed from the rolls and the mill put into operation for the intended purpose. After the heater has been removed, the filling blocks 115 shown in Figure 10 are placed upon the offset or depressed portion 13 of the bar 12, and held fixed relatively by the key 17 hereinabove described, the association of these blocks and key with the bar 12 being clearly 120 illustrated in Figure 9. During the use of 125 the heater however, the rolls 10 and 11 are held suitably spaced apart by means of the asbestos spacing element 43 so that the heat from the various burners is not only directed against the opposite sides, top and bottom 130 of said rolls but is also allowed to pass between the rolls and circulate thereabout, so that the entire area of each roll is uniformly heated. As hereinabove stated, the rolls are protected from the flames by means of 130

the baffle plates 41 which are arranged between the rolls and each series of burners as clearly illustrated in the drawings.

In Figure 6, I have shown a modified form of the invention, wherein the heater casing constituting the body of the heater is made into sections 45 and 46 suitably connected together as at 47 at the upper ends thereof, the lower ends of these sections being spaced as clearly shown. In this form of the invention, it is not necessary to make use of a bar 12 having an offset or depression portion 13 as above described, the heater being used in connection with the ordinary straight bar 48, inasmuch as the casing does not support a large battery or series of burners as shown in Figure 1. In other words, this form of the invention is used with the rolls 49 and 50 which are adapted to revolve while being heated, as distinguished from the arrangement shown in Figure 1, where the rolls 10 and 11 remain stationary. The lower ends of the sections 45 and 46 of the casing are connected by a plate 51 of substantially V-shaped formation in cross section, the plate being received by the adjacent ends of the respective sections of the casing and having its intermediate portion reposing upon the bar 48 as illustrated in Figure 6. The design of this plate 51 is clearly shown in Figure 13. In addition to this construction, the heater is supported by adjustable jacks which are preferably of the construction shown in Figure 12, each jack including a base 52, and threaded rods 53 and 54, the former being associated with the base, while the latter is associated with the adjacent section of the casing, the rods being connected by a sleeve 55. This structure is similar to the ordinary turn buckle, so that the casing can be raised or lowered incident to the rotation of the sleeve 55 in one or the other directions. The respective sections of the casing are adapted to be lined in the same manner hereinabove described in connection with the preferred embodiment of the invention. Now, it will be noted upon inspection of Figure 6 that there is only two series of burners 56 used in connection with each section of the casing, these burners being arranged as shown in Figure 6 to direct the heat against the rolls 49 and 50 at points adjacent their points of contact. The supply pipe 57 is suitably coupled to the fuel and air supply pipes 58 and 59, and all of these pipes are equipped with a suitable valve 60.

When using this form of the invention, the burners 56 and 57 are lighted and the rolls slowly rotated so that the entire area of each roll is subjected to the heat from the burners while they are being rotated. It is manifest that with either form of the invention, the rolls can be expeditiously heated

prior to the use of the mill so that a high grade or character of work can be accomplished from the very outset.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

1. A heater for sheet mill rolls comprising a heat retaining casing made in sections and designed to completely enclose said rolls, means for holding said sections associated, burners supported by said casing and arranged to direct their heat toward the rolls, baffle plates arranged between the rolls and burners, and against which the heat is initially directed, and valves for said burners.

2. A heater for sheet mill rolls, comprising a heat retaining casing designed to completely cover said rolls, spaced series of burners supported by the opposed sides of the casing longitudinally of the rolls, and arranged to direct their heat toward the latter, fuel and air supply pipes supported by the casing and having valve control communication with said burners, a baffle plate interposed between each series of burners and the adjacent roll, and a valve for each burner.

3. A heater for sheet mill rolls comprising a heat retaining casing made up in sections and designed to unitedly enclose said rolls when the latter are stationary, means for connecting the said sections of the casing together, spaced series of burners supported by each section and arranged to direct the heat toward and about said rolls, baffle plates arranged between each series of burners and the adjacent roll, means for supporting said baffle plates within the casing, fuel and air supply pipes arranged upon the casing and having valve controlled communication with said burners, and a valve for each burner.

4. A heater for sheet mill rolls comprising a heat retaining casing designed to completely enclose said rolls, a series of burners supported on the opposite sides of the casing and arranged to direct the heat against said rolls at points adjacent their points of contact, and to heat the entire area of said rolls, while the latter are rotated, baffle plates against which the heat is initially directed, said casing having spaced draft openings, fuel supply pipes supported by the casing, and valves controlling the communication between the pipes and said burners.

5. A heater for sheet metal rolls comprising a heat retaining casing made up in sections, and designed to unitedly enclose said

rolls, said sections having their lower end spaced apart, an angular plate supported by said sections and arranged to close the lower end of said casing, means supporting said casing, a series of burners supported by each section and arranged to direct their heat toward the rolls at points adjacent their points of contact, whereby the entire

area of each roll is heated during the rotation of the latter, fuel supply pipes supported by the casing and communicating with said burners and valves controlling said communication.

In testimony whereof I affix my signature.

JESSE C. LEAR.
